UNITED STATES PATENT OFFICE

MYER METZGER, OF CHICAGO, ILLINOIS

DISPLAY STAND

Application filed June 7, 1926. Serial No. 114,090.

This invention relates to improvements in display stands, particularly adapted, though not necessarily limited in its use, for holding and displaying articles or packages to be piled thereupon or for holding a container in which the articles are packed, in such a manner that the articles will be displayed to the best advantage and in a convenient position so that they may be readily dispensed.

10 A further object is to provide an improved stand of this character constructed of a single piece of sheet material maintained in a flat condition for shipment and storage purposes and adapted to be bent into shape for use, the 15 blank being provided with means for facilitating in the bending thereof and for indicating the point or lines upon which the different portions of the blank are to be bent to shape the stand.

20 To the attainment of these ends and the accomplishment of other new and useful objects as will appear, the invention consists in the features of novelty in substantially the 25 construction, combination and arrangement of the several parts hereinafter more fully described and claimed and shown in the accompanying drawings illustrating this invention, and in which—

Figure 1 is a top plan view of one form of 30 blank.

Figure 2 is a view similar to Figure 1, showing the circumferential edge of the blank folded upon itself to re-enforce the same.

Figure 3 is a perspective view of the blank 35 folded into shape and illustrating several packages supported by the stand.

Figure 4 is a top plan view of another form of blank, showing in dotted lines the edges of the blank folded back upon itself to re-enforce the same.

Figure 5 is a perspective view of the blank shown in Figure 4, bent to form the stand and showing in dotted lines a container placed upon the stand.

45 Figure 6 is a top plan view similar to Figure 1, of another form of blank.

Figure 7 is a top plan view similar to Figure 6, showing the edges of the blank folded upon itself to re-enforce the blank.

50 Figure 8 is a perspective view of the blank

shown in Figure 7 bent into shape to form a stand and showing in dotted lines a container placed upon the stand.

Referring more particularly to the drawings and to the form of the invention shown in Figures 1 to 3, the blank is formed of a single piece of sheet material and embodies a body portion 10, having lines of perforations or apertures 11, 12 and 13 extending thereacross and at predetermined points in the length of the blank.

The circumferential edge of the blank is bent upon itself as at 14 for re-enforcing the edges and each of the lines of perforations 11, 12 and 13 is provided at the extremities thereof with openings 15 so that when the edges of the blank are folded these openings 15 will extend through the edge of the blank to facilitate in the bending of the blank.

The blank thus formed is bent upon the lines of perforations 11 to form an end portion 16 that extends downwardly from the body portion 10. The other end of the blank is bent along the line of perforations 12 to form an upwardly extending portion 17, and this upwardly extending portion is also bent along the line of perforations 13 to form a downwardly and outwardly inclined portion 18.

The portion 17 forms an abutment wall for the articles 19 which are placed upon the body portion 10, and the edge formed by the bend at the bottom of the portion 17 cooperates with the free extremity of the downwardly bent portion 16 to hold the body portion 10 in an upwardly inclined position.

The free extremity 20 of the portion 18 terminates preferably substantially in alignment with the edge formed by the base of the bent portion 17 and constitutes an extended exposed surface on the stand for the reception of advertising or descriptive matter.

It will be manifest that a stand thus constructed will be of a strong and durable construction and when it is desired to ship or store the stand the bent portions may be deflected or straightened out so that they will assume positions substantially in the same plane as the plane of the body portion 10.

In the form of the invention shown in

Figures 4 and 5, the blank is formed and the stand is shaped in the same manner as that shown in Figures 1 to 3, and in addition thereto portions 21 of the body portion 10 preferably adjacent the line of perforations 11 are cut out and deflected upwardly so as to project above the upper surface of the body portion 10 and in a direction opposite to the direction in which the portion 16 extends from the body 10. These upwardly projecting portions 21 co-operate with the upwardly extending portion or wall 17 at the forward end of the body portion 10 so that a container 22 may be placed upon the stand, the forward portion of the container abutting the wall or portion 17, while the upwardly extending portions 21 stand adjacent the rear of the container and serve as a means for preventing accidental displacement of the container from the stand.

In the form of the invention shown in Figures 6 to 8, the blank embodies a body portion 23 having lines of perforations 24, 25 and 26 thereacross. The end of the blank 25 is bent upwardly along the line of perforations 25 to form an upwardly projecting wall 27 and the upwardly projecting portion thus formed is bent along the line of perforations 26 downwardly and outwardly to form the portion 28 which provides an extended area for the reception of advertising or descriptive matter.

The other end of the blank is bent upwardly along the line of perforations 24 to form an upwardly projecting portion 29 that extends for a considerable distance above the upper surface of the body portion 23. The free extremity of the upwardly extending portion 29 is shaped to form a forwardly projecting ledge 30 and the portion 29 may be arranged at any desired angle with respect to the body portion 23.

A portion of the body 23 is cut out as at 31 and a line of perforations 32 is provided in the body portion 23 adjacent one end of the cut out portion 31.

The portion 31 is deflected downwardly so as to project below the body portion 23 to serve as a foot or support which co-operates with the edge forming the junction between the body portion 23 and the upwardly projecting wall 27, to hold the body or stand in an upwardly inclined position.

With this form of stand a container 33 may be placed in position thereupon and a cover or lid 34 of the container 33 may be opened and the free extremity of the cover passed beneath the overhanging ledge 30 so as to hold the cover in an open position and against accidental closing.

In this form of the invention, as in the other forms, it will be manifest that when it is desired to ship or store the blank the various bent portions may be straightened

out so that they will assume positions within the plane of the body portion 23.

With this invention it will be manifest that there will be provided a light, simple and durable stand, all constructed from a single piece of sheet material and which may be shipped or stored in a flat or knocked down condition, the lines of perforations also serving as indicators or guides for directing the user in deflecting or bending of the various parts to shape the stand for use.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. A stand of the character described embodying a body portion formed from a single piece of sheet material, portions of the body spaced from each other being bent in opposite directions, one of said portions extending upwardly and the other downwardly from the body, the latter said portion co-operating with the lower edge of the upwardly turned portion to support the body in an upwardly inclined position, another portion of the body adjacent the said downwardly bent portion forming a projecting portion extending above the upper surface of the body and spaced from and co-operating with the first recited upwardly turned portion to hold an article therebetween.

2. A stand of the character described embodying a body portion formed from a single piece of sheet material, portions of the body spaced from each other being bent in opposite directions, one of said portions extending upwardly and the other downwardly from the body, the latter said portion co-operating with the lower edge of the upwardly turned portion to support the body in an upwardly inclined position, another portion of the body adjacent the said downwardly bent portion forming a projecting portion extending above the upper surface of the body and spaced from and co-operating with the first recited upwardly turned portion to receive and hold an article therebetween, the free end of the first recited upwardly turned portion being shaped to form a downwardly and outwardly extending portion.

3. A stand of the character described embodying a body portion formed from a single piece of sheet material, portions of the body spaced from each other being bent in opposite directions, one of said portions extending upwardly and the other downwardly from the body, the latter said portion co-operating with the lower edge of the upwardly turned portion to support the body in an upwardly inclined position, another portion of the body

adjacent the said downwardly bent portion forming a projecting portion extending above the upper surface of the body and spaced from and co-operating with the first recited 5 upwardly turned portion to receive and hold an article therebetween, one of the said bent portions being cut out of the body within the confines of the peripheral edge of the body.

4. A stand of the character described employing a body portion formed from a single piece of sheet material, portions of the body spaced from each other being bent in opposite directions, one of said portions extending upwardly and the other downwardly from 10 the body, the latter said portion co-operating with the lower edge of the upwardly turned portion to support the body in an upwardly inclined position, another portion of the body adjacent the said downwardly bent portion 15 forming a projecting portion extending above the upper surface of the body, a portion of the last recited upwardly extending portion forming a forwardly projecting ledge.

5. A stand of the character described employing a body portion formed from a single piece of sheet material, portions of the body in alignment with and spaced from each other being bent in opposite directions, one of said portions extending upwardly and the other 20 downwardly from the body, the latter said portion serving to hold the body in an upwardly inclined position and the portion of the body in proximity to the said downwardly bent portion forming an upwardly 25 extending portion projecting for a considerable distance above the upper surface of the said body, and a forwardly projecting formation on the last recited upwardly extending portion and spaced above the said inclined 30 portion of the body.

In testimony whereof I have signed my name to this specification on this 3rd day of June, A. D. 1926.

MYER METZGER.
